Primary Examiner — Zenia I Bennett

(74) *Attorney, Agent, or Firm* — Dickinson Wright PLLC

(57) **CLAIM**

The ornamental design for a clasp, as shown and described.

DESCRIPTION

FIG. 1 is a perspective view of a first embodiment of my new design for a clasp;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view showing the clasp in the open position for clarity;

FIG. 9 is a perspective view showing an exploded view of the clasp for clarity;

FIG. 10 is a perspective view of a second embodiment of my new design for a clasp;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a perspective view showing the clasp in the open position for clarity; and,

FIG. 18 is a perspective view showing an exploded view of the clasp for clarity.

The broken lines in the drawings are included for the purpose of illustrating portions of the clasp that form no part of the claimed design.
